(57) **CLAIM**

The ornamental design for a baby bath seat, as shown and described.

DESCRIPTION

FIG. 1 is a left, front, bottom perspective view of a baby bath seat, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a right, front, top perspective view thereof;

FIG. 9 is a rear perspective view thereof; and,

FIG. 10 is an enlarged view of portion of FIG. 9.

The broken lines in the figures are demarcating enlarged areas and form no part of the claimed design.
